UNITED STATES PATENT OFFICE.

GEORGE G. PERKINS, OF LYNN, MASSACHUSETTS.

SHOE MACHINERY.

Application filed July 11, 1927. Serial No. 204,702.

My invention relates to shoe machinery and more particularly to the so-called edge setting machine, designed and used in finishing the top lifts on wood heels, and heels made of other materials. The objects of my invention are to speed up production; to minimize production costs; to improve the quality of finish; to eliminate holding jacks in heel finishing machines; to provide an improved finishing machine designed to pound and rub so as to literally drive the finish into the polished surface; to provide a new and novel oscillating iron movement; to provide a new and novel iron embodying a ridged surface either in one piece or in assembled units; to provide a new and novel combination comprising a movable edge iron with an adjustable gauge plate adaptable to set the iron at designated distances and at varying angles in relation to the edge iron; to provide means for exerting an adjustable spring pressure on the heel while the finish is being applied to the top lift, so as to furnish a firm yet yielding pressure, insuring no injury to the heel surface or heel cover at the points of contact; to provide a pressure means adaptable to travel with the surface of the heel as the top lift is rotated on the edge iron thus eliminating friction, surface fracture and injury to the heel cover or finish; to provide a new and novel combination of an edge iron with a travelling spring pressure; to provide a new and novel combination of an edge iron, a travelling spring pressure and an adjustable guide plate or gauge; to provide quickly interchangeable pressure arms; to provide a travelling pressure means adaptable to rest against the surface of a heel in the process of finishing, deriving its horizontal motion from the heel as said heel is rotated, and utilizing a combination spring and foot lever pressure for vertical motion; to provide a new and novel adjusting means on the pressure lever so as to render it capable of furnishing varying loads and adaptable to heels of various sizes; and to furnish the various other advantages and results made evident from the following specification.

I accomplish the objects of my invention as shown in the accompanying drawings, which form a part of this specification, and in which Figure 1 shows a front view of my machine. Figure 2 shows a partial side view of the machine frame at its top portion, the edge iron and back guide plate. Figure 3 shows the edge iron and pressure arm with a heel, in

position for edge setting and finishing, between the two. Figure 4 shows the detail of the assembled iron. Figure 5 shows a sectional view of the iron. Figure 6 shows the detail of my adjustable spring pressure bar. Figure 7 shows the detail of my W shaped auxiliary pressure arm designed to care for the travel of the heel corners so as to insure a steadier and more uniform turning of the top lift edge against the finishing iron, together with a heel in position thereon, and a partial front view of the finishing iron. Figure 8 shows the same parts as Figure 7 with the heel in a progressive turning position. Figure 9 shows the heel in a further progressive turning position. Figure 10 shows the heel in its position at the final finishing stage.

Referring again to Figure 1, A shows the machine frame. A² shows the fulcrum arm extending from the frame A. B shows an eccentric shaft. B² and B³ show eccentric connecting arms. B⁴ shows a fulcrum pin on which the arm B³ oscillates. C shows the finishing iron holder. C² shows the units of the finishing iron. D shows the pressure arm. D² shows the auxiliary pressure arm hinged on the pressure bar F by the tightening bolt D³. D and D² are hinged and shaped to be positioned alternately in the same alignment when in use. E shows the pressure bar holder extending from and connected to the frame A at E², adaptable to guide the pressure bar F when the same is moved vertically and horizontally. G shows the foot lever hinged at G² on the frame A and connected with the pressure bar F at F². Foot pressure is intended to be exerted at the end G³ to move the pressure bar to its operative position. H shows an adjusting collar encircling the pressure bar F, fitted with a hand screw H² for tightening and holding the pressure spring H³, so as to provide the required pressure on heels of varying sizes. H⁴ shows the connecting member between the pressure bar F and the foot lever G designed to receive one end of the pressure lever F, allowing its free play therein and affording unrestricted adjustments. I shows my adjustable gauge plate. Since the connecting member H⁴ is pivoted to foot lever G a limited swinging movement or horizontal movement of the pressure bar is set up as the finishing iron oscillates on the heel, and limited vertical movement is also attained by the sliding movement of member F during the operating of my device against the pressure of the

spring H³; the two movements which accordingly are transmitted to the pressure bar may be termed "traveling" since the pressure bar follows to a limited extent the configuration 5 of the heel and is influenced by the oscillating movement of the finishing iron.

Referring again to Figure 2 I² shows the pivot on which the gauge plate I is mounted so as to allow various angular adjustments, 10 in any of which adjustments it is held by the from the finishing iron C is regulated by the threaded shaft J and nuts J² and J³.

Referring again to Figure 3, K shows a 15 heel in position for finishing between the iron C² and the pressure arm D.

Referring again to Figures 7, 8, 9 and 10, K² shows the heel in its varying travelling 20 positions, during the process of finishing.

Referring again to Figure 4, the units C² of the composite iron are assembled in the holder C so that the high points on their outer or contacting surface C³ form an arc 25 in proper ratio to the oscillating movement created by the eccentric B and arm B², thus during the arms oscillating movement, insuring successive and equal contacts of the respective high points against that portion of the heel being finished. The successive and 30 equal contact of the respective high points is broken by the smaller radius on each side of the high point as the oscillating movement progresses, and as the successive units C² come into contacting position, pounding and rubbing 35 as they pass. It will be seen that the pounding effect is created by the depressions or valleys on the surface C³ of the irons together with the spring force exerted by the pressure bar. The series of finishing units in 40 the iron minimize the breaking of contact between the heel and the iron during the free hand turning of the heel by the operator, during the finishing process, thus speeding production and insuring improved results.

Referring again to Figures 7, 8, 9 and 10, it will be recognized that the W shaped form 45 of the arm D² is designed to facilitate the free hand turning of the heel by the operator during the finishing process. Its use is particularly adaptable in the finishing of large heels. Smaller heels, as shown in Figure 3 do not require the W shaped arm. When 50 smaller heels are to be finished the bar D² is swung on bolt D³ to its downward or inoperative position, and the bar D¹ is swung up to its operative position as shown in Figure 1.

Similar letters of the reference refer to similar parts throughout the various views.

While I have illustrated and described a 60 preferred construction for carrying my invention into effect, this is capable of variation or modification without departing from the spirit of the invention. I therefore do not wish to be limited to the exact details of construction herein set forth but desire to avail

myself of such variations and modifications as come within the scope of the appended claims.

Having thus described my invention I claim as new and desire to secure by Letters Patent 70 of the United States of America:

1. In a machine of the kind described, an edge iron formed of separate units set side by side and certain of which are in advance of the others to provide an arcuate face, each 75 of said units having an irregular face providing a corrugated surface adaptable for successive contacts with material on which a finish is to be applied and adjustable and slightly movable means for pressing said material against said iron.

2. In a machine of the kind described, an edge iron formed of separate units adjustable with respect to each other, and each unit having a curved face adapted to provide in assembly a corrugated surface, means for oscillating said iron against material on which a finish is to be applied, and adjustable means for pressing said material against said iron, said means mounted for limited movement in 80 two directions during the pressing operation.

3. In a machine of the kind described, an edge iron, means for oscillating said iron against material on which a finish is to be applied, and adjustable travelling means for pressing said material against said iron, said travelling means comprising a W shaped pressure arm.

4. In a machine of the kind described, an edge iron having a corrugated surface the high and low points thereof being adapted for successive contacts with material on which a finish is to be applied, adjustable travelling means for pressing said material against said iron, and an adjustable gauge plate adaptable to be set at varying distances and angles 100 from said iron.

5. In a machine of the kind described, an edge iron having a corrugated surface, means for oscillating said iron against material on which a finish is to be applied, adjustable and oscillating means of pressing said material against said iron and an adjustable gauge plate adaptable to be set at varying distances and angles 110 from said iron.

6. In a machine of the kind described, an edge iron, means for oscillating said iron against material on which a finish is to be applied, adjustable travelling means for pressing said material against said iron, and an adjustable gauge plate adaptable to be set at varying distances and angles 120 from said iron.

7. In a machine of the kind described, an edge iron, means for actuating the edge iron to rotate a heel, oscillatable means for exerting a firm yet yielding pressure against a heel in the direction of the edge iron during the process of edge finishing, and adaptable to move both horizontally and vertically with the sur- 125 130

face of the heel as the top lift is rotated relative to the edge iron.

8. In a machine of the kind described, an oscillating burnishing iron, a pressure bar, interchangeable pressure arms hinged on said pressure bar and movable to be easily and quickly aligned in relatively the same position with regard to the burnishing iron.

9. In a machine of the kind described, a finishing iron, yielding pressure means adaptable to hold a heel during the process of finishing against the finishing iron, said means so mounted as to move both horizontally and vertically with the surface of the heel as the

top lift thereon is rotated relative to said edge iron.

10. In a machine of the kind described, a sectional pressure lever the sections of which telescope, a pressure bar carried by the lever, a finishing iron cooperating therewith to hold a heel therebetween, a spring between the sections of the lever, and means for adjusting the compression of the spring thereby to render said pressure bar capable of holding various sizes of heels and exerting different pressures thereon.

In testimony whereof I affix my signature.

GEORGE G. PERKINS.
